UNITED STATES PATENT OFFICE.

FERDINAND A. HILKER, OF RACINE, WISCONSIN.

SHOE-RETISSING DEVICE.

Application filed August 9, 1923. Serial No. 658,582.

To all whom it may concern:

Be it known that I, FERDINAND A. HILKER, a citizen of the United States, residing at Racine, in the county of Racine and State 5 of Wisconsin, have invented certain new and useful Improvements in Shoe-Retipping Devices; and I do declare the following to be a full, clear, and exact description of the invention, such as will enable 10 others skilled in the art to which it appertains to make and use the same.

My invention aims to provide an extremely simple and inexpensive, yet an efficient and desirable device for retipping 15 old shoes, said device including a metal toe last for snug reception in the tipped portion of a shoe, a thrust device for forcing the last snugly into the shoe and holding it, and a novel connection between the thrust 20 device and the last, permitting relative angling of these parts when inserting or removing the retipper.

With the foregoing in view, the invention resides in the novel subject matter herein- 25 after described and claimed, the description being supplemented by the accompanying drawings.

Figure 1 is a horizontal sectional view partly in elevation, showing the application 30 of the retipper to a shoe.

Fig. 2 is a vertical longitudinal section partly in elevation.

Fig. 3 is a side elevation of the retipper, partly in section, showing the manner of 35 angling the thrust device and the toe last.

In the drawings above briefly described, the numeral 1 designates a preferably solid metal toe last of a size and shape to fit snugly into the tip-covered toe portion of 40 the shoe to be retipped the rear end of the last, being provided with a pair of horizontally spaced vertically parallel ears 2 and having a socket 3 between said ears.

An adjustable thrust device 4 is associated 45 with the last 1 for holding the latter snugly in the toe of a shoe. This thrust device preferably consists of a front non-rotatable section 5, a rear rotatable section 6 having a threaded connection with said front section, 50 and a heel block 7 swivelled on the rear end of the section 6. The section 5 is preferably formed of a length of rod with its front end flattened slightly and received slidably between the ears 2, said front section having 55 a longitudinal slot 8 between the ears, through which a removable pin 9 passes,

said pin being driven through openings 10 in the ears. In front of the slots, the section 5 is preferably reduced to form a stud 11 for reception in the socket 3, and a shoulder 12 at the rear end of said stud to bear against the rear end of the last 1 and thus take strain from the pin 9. It will be seen that when the thrust device 4 is extended forwardly until the stud 11 is received in the socket 3, said thrust device will have rigid relation with the toe last 1, but when relative movement of the last and thrust device is effected to withdraw the stud from the socket, the two parts may be 60 angled as disclosed in Fig. 3, which permits the device to be easily inserted into or removed from the shoe.

A shoe to be retipped, has its outer sole removed or turned back at the front end, a new tip is then stitched to the shoe upper, and the edges of the tip are turned inwardly under the shoe as indicated in Fig. 2. Then, the last 1 is forced snugly into the toe of the shoe and held in this position by the 75 thrust device 4. Nails may now be driven through the inturned edges of the new tip to secure them in place, and the last 1 will clinch these nails as disclosed in Fig. 2. Then, the old sole may either be secured 80 back in place, or a new sole applied.

In placing my device upon the market, I intend to provide a plurality of the toe lasts 1, of different sizes and shapes and I prefer also to furnish at least two of the thrust 85 screws 5, of different lengths, thus permitting the device to be adapted for use on shoes of different sizes and shapes.

As excellent results may be obtained from the details disclosed, these details are preferably followed, but within the scope of the invention as claimed, numerous minor 95 changes may be made.

I claim:—

1. A shoe retipper comprising a metal 100 toe last shaped to snugly fit into the toe of a shoe to be retipped, said last having a flat lower side at least equal in length to the average shoe tip and adapted for clinching nails driven through the inturned edge of a tip applied to the shoe, and an adjustable thrust device connected with said last and adapted to engage the heel portion of the shoe upper to hold said last snugly in place.

2. A shoe retipper comprising a metal toe 110 last of a size and shape to snugly fit into the toe of a shoe to be retipped, said last

having a flat lower side for clinching nails driven through the inturned edge of a tip applied to the shoe, the rear end of said last having a pair of horizontally spaced 5 vertically parallel ears and a socket between them, an adjustable thrust device whose front end is received slidably between said ears and adapted for reception in said socket when the retipper is in use, said 10 thrust device having a longitudinal slot between said ears, and a removable pin passing through said ears and said slot, rearward

sliding of said thrust device serving to permit withdrawal of its front end from the socket, allowing upward swinging of said thrust device for easy removal of the retipper from the shoe. 15

3. A structure as specified in claim 2; said thrust device having a shoulder to contact with the rear end of the last and 20 prevent strain on said pin.

In testimony whereof I have hereunto affixed my signature.

FERDINAND A. HILKER.
